CARD PUNCH

Le Roy M. Osborne, San Rafael, and Berger
Stockfleth, Paradise Cove, Calif.

Application February 11, 1949, Serial No. 75,777

2 Claims. (Cl. 30—229)

1

Our invention relates to means for cutting or removing a portion of material from a sheet such as a card, paper and the like and is particularly concerned with a punch for accurately removing a portion of a sheet or card from a predetermined location.

While numerous forms of punches for use by hand have heretofore been available, none of them, so far as we know, is of general use in accurately providing a specially removed portion from the margin or edge of a card or the like, particularly if accuracy in location of the removed portion is essential and particularly insofar as the transverse location is concerned. This matter becomes of considerable importance when punched cards are utilized for the purpose of recording or representing data and is a vital factor when the location of the punched out portions, both transversely and longitudinally is relied upon in representing or storing the data.

It is therefore an object of our invention to provide a hand punch for use on cards or the like which does not require any change in technique or knowledge of an operator for its use, but does provide an accurate punched out portion.

Another object of the invention is to provide a card punch in which the positioning or location of the punch, both transversely and longitudinally with respect to a designated part of a card or the like, is easily and almost automatically effectuated.

A further object of the invention is to provide a card punch in which punches can be made in accurate positions and locations with regard to each other not only longitudinally and transversely but also in the rotary or polar sense.

A still further object of the invention is to provide a generally improved card punch.

Other objects together with the foregoing are attained in the preferred embodiment of the invention illustrated in the accompanying drawings in which

Figure 1 is a perspective of a punch constructed in accordance with the invention.

Figure 2 is a view to an enlarged scale of the punch shown in Figure 1, portions being broken away to reduce the size of the figure and some parts being illustrated in a longitudinal cross-section.

Figure 3 is a cross-section, the plane of which is indicated by the line 3—3 of Figure 2, the view being to a still further enlarged scale and showing only the actual perforating or cutting part of the punch mechanism.

In its preferred form, the card punch of the invention comprises a pair of levers pivoted to-

gether for movement between an open position and a closed position. One of the levers is provided with a generally planar platform having a pair of laterally spaced abutments having coplanar front faces upstanding from each side of the platform and between them leaving space in the platform for an aperture disposed between or in part between the abutments themselves. The other lever of the pair is formed with a cutting head on it which in the open position of the punch is free and clear of the aperture but which in the closed position of the punch extends into and rather closely occupies the aperture. In addition, the cutting head has formed on it a projection, preferably disposed between the lateral sides of the head and near the abutment walls on the first lever and located in such a way with respect to the cutting head that it serves as a positioning device for a card to be punched. The extension or projection is so disposed and located and is of such a dimension that it never moves out of the aperture but always, in both open and closed positions of the punch, extends into the mentioned aperture.

While the paper punch of the invention is applicable to many different uses and is embodied in variant forms depending in part upon such different uses, it has been successfully embodied and employed as shown herein and especially for use in connection with a card of the type disclosed in our co-pending application entitled "Punch Card," filed February 11, 1949, with Serial No. 75,778.

The punch card, partially illustrated herein in Figure 3, is a sheet 6 of suitable material having an edge 7 or margin formed not only with a general rectilinear boundary 8 but also with indentations 9 or scallops or cut-out portions located accurately with respect to each other laterally or transversely of the card and extending into the edge 7 of the card a predetermined distance. The card usually carries further indicia, not illustrated herein because they form no part of the present invention, but which are related by position to the notched or scalloped portions 9. The form of the card and its normal indicia are such that some of the card is cut away or punched out from the edge in order to alter or designate the indicia or display and therefore to alter or change the data indication of the card.

In accordance with our invention, we utilize the accurate relationship between the indicia present on the card 6 and the indentations or notches 9 in connection with our punch to afford an easy, quick, and accurate data indicating card structure.

The punch itself, for this purpose, includes generally a pair of levers 12 and 13 of the customary sort, crossed and articulated by a pivot pin 14 in the usual fashion. The contour of the levers adjacent the pivot 14 is such that in one position, an open position, a stop 16 on one of the levers is engaged by a stop 17 on the other lever to limit their opening movement. The levers are normally urged into such open position by a coil spring 18 situated between the handles and held in position by projections 19 and 21 thereon. As so formed and arranged, the levers are movable between an open position, as shown in Figures 1 and 2, and a closed position in which the handles of the levers 12 and 13 are close together.

In accordance with the invention, one of the levers, for example the lever 12, adjacent the pivot connection 14 is bifurcated or forked to provide a side wall 22 and a side wall 23. These walls are extended forwardly and downwardly to provide sides of a compartment 24 formed in the handle for the reception of punched out portions of cards. The lever is also provided with a rearward wall 26 for the compartment and in which a fastening 27 is fixed to secure in rotated position a cover plate 28 adapted to form the lower boundary of the compartment 24. A finger projection 29 assists the user in swinging the plate 28 to one side when the contents of the compartment 24 are to be discharged.

The compartment is likewise bounded by a forward wall 31, having a rounded nose 32. This extends to merge into an upper platform 33 not only providing an upper boundary for the compartment 24 but also providing a generally planar platform 34 approximately radial to the axis of the pivot pin 14. Part of the upper wall 33 is not co-planar with the forward platform 34 but rather is raised slightly, although it tapers rearwardly, to provide a forward ledge 36.

The upper wall 33 is not continuous but rather is interrupted or perforated or pierced to provide a through aperture 37 extending from the platform 34 into the compartment 24 and extending between the side walls 22 and 23. Preferably, the aperture 37 is given a standard contour, for example circular cylindrical, and in effect merges with the ledge 36. In order to afford a special or desired contour of the aperture for punch purposes, the upper wall 33 itself in its forward portion, at least, is somewhat enlarged to provide a socket 38 into which is pressed and positioned a female cutting member 39 having a circular cylindrical outside contour but having a special inner cutting contour 41, in this instance substantially a parabola.

The parabolic cutting edge 41 is of such an extent that it is disposed laterally between the side walls 22 and 23, and extends longitudinally into the space 42 between the walls 22 and 23. Stated differently, the side walls 22 and 23 extend forwardly with respect to the planar platform 34 beyond the confines of the opening 41 and in fact end in upright faces 43 and 44 which are co-planar transversely of the card punch and extend substantially perpendicular to the planar face of the platform 34 so that the forward wall ends 43 and 44 serve accurately as abutments or stops.

The other lever 13 of the punch has a central finger 46 disposed between the side walls 22 and 23 and projecting forwardly between such walls to a point adjacent the aperture 37. The forward end of the finger is provided with an enlarged cutting head 47 having in a transverse cross-

5
10
15

section a suitable shape, generally a parabolic contour approximately to fit the parabolic aperture 41. While the shape illustrated in Figure 3 is preferred, other suitable and complementary shapes of the cutting head and of the die 39 can be readily provided. The cross-sectional shape of the cutting head 47 is extended as a surface of revolution about the axis of the pivot pin 14 so that as the handle 12 and 13 are squeezed together by the user, the cutting head 47 can move from its first or open position, entirely out of the aperture 37, into a second or closed position in which at least part of the cutting head extends into the aperture 37 or into the general zone of the die 39.

In the normal, open position of the punch, a card placed on the planar platform 34 and thrust toward the pivot pin 14 does not contact the cutting head 47 at all and is not stopped until it reaches the abutments 43 and 44. That relationship affords a longitudinal alignment between the card edge and the punch and provides for a definite depth or longitudinal dimension of cut.

In accordance with our invention, we provide additional means for accurately positioning a card. Such means include a projection 51 depending from the cutting head 47 and in fact forming part of it in usual manufacture. The projection 51 in cross-sectional contour is preferably comparable to the die and, as shown, is of parabolic shape. It is of a sufficient extent always to have at least a portion lying within the aperture 37 below the cutting die 39 so that some part of the projection 51 is always in the path of a card inserted into the punch and being moved toward the abutments 43 and 44. The projection 51 is not itself a cutting member as its forward or leading edge is rounded parabolically as shown in Figure 3 especially. It is disposed equidistantly between the side walls 22 and 23 and extends in part ahead of the abutment walls 43 and 44 and in part behind them.

In the usual use of this punch, a card of the sort shown in Figure 3 is introduced into the space between the upper and lower levers, that is between the cutting die 39 and the enlarged head 47 until a notch 9 or scallop or cut-out portion of the card is in engagement with the projection 51. Such interengagement between that projection and the card not only serves in addition to gage the depth of the punch to be made in the edge of the card but especially locates the punch laterally or transversely with respect to the card. Furthermore, in the initial engagement of the card with the punch, as soon as the card is in abutment with the walls 43 and 44, no rotation or polar movement of the card is possible. Except for a vertical motion, therefore, the card is exactly and entirely positioned. Since the notches 9 are slightly larger than the nose or leading edge of the projection 51, even an unskilled operator simply by moving the punch along the straight edge of the card until the appropriate notch is encountered and then forcing the card and punch slightly closer together can readily locate the punch and the card with extreme accuracy both longitudinally and laterally and with respect to any rotational displacement.

As soon as the card and punch have been relatively located as described, the operator squeezes the levers 12 and 13 from their open position into their closed position and the cutting portion or enlarged head 47 descends into the cutting die 39 severing an outline of the card

comparable to the parabolic outline 41. During that time, the depending projection 51 slides or in effect rotates against the notch 9 in the card thus maintaining the card's position from the time of original positioning of the card entirely through the cutting operation. It is thus not possible to displace the card and spoil the cut as to accuracy by accidentally shifting or moving the punch as the cutting operation is progressing. As soon as the projection 41 has passed entirely into the cutting die 39, a part of the card has been severed and falls into the compartment 24 for later removal. Upon the severance of the portion corresponding to the outline 41, the card itself is entirely free from the punch and the two 15 are then readily separated.

We claim:

1. A card punch comprising a pair of levers pivoted together for movement between an open position and a closed position, the first of said levers having a planar platform and a pair of laterally spaced transversely aligned abutments upstanding from said platform, there being an aperture in said platform in part disposed between said abutments, a cutting die mounted in said aperture flush with said platform, the second of said levers having a cutting head thereon in said open position being out of said die and in said closed position extending into said die, and a projection on said cutting head at the side adjacent the lever pivot and extending into said aperture outwardly of and between said abutments.

2. A card notching device, comprising: a pair

of levers pivoted together and respectively carrying punch and die members, card positioning means on said device, said card positioning means defining spaced surfaces engageable with spaced portions of an edge of a card to be notched, said card positioning means further defining transverse surfaces extending laterally from a plane containing said spaced surfaces, said transverse surfaces being generally parallel to the direction of relative movement between said punch and die members and engageable with the sides of indentations in a card edge to position said notching device in predetermined position along the edge of said card.
